[21] Appl. No.: 463,802

[57] CLAIM

The ornamental design for a food shredding device, as shown and described.

DESCRIPTION

FIG. 1 is a perspective view of a food shredding device, showing my new design;

FIG. 2 is a side elevational view thereof; and

FIG. 3 is a cross-sectional view thereof taken substantially along the line 3—3 of FIG. 2.
